UNITED STATES PATENT OFFICE.

PETER MACGREGOR, OF OTTAWA, ONTARIO, CANADA.

DETACHABLE TAB.

1,067,531.

Specification of Letters Patent. Patented July 15, 1913.

Application filed April 17, 1911. Serial No. 621,703.

To all whom it may concern:

Be it known that I, PETER MACGREGOR, of 19 Strathcona avenue, in the city of Ottawa, Province of Ontario, Dominion of Canada, have invented certain new and useful Improvements in Detachable Tabs, of which the following is a specification.

My invention relates to improvements in detachable tabs, and the objects of my invention are to provide an inexpensive form of tab which may be adjustably connected to the member or object on which it is to be used, and further to provide an improved method of effecting such connection.

15 The tab may be used in a system of indexing on folders, filing cases, spacing sheets and the like. It may also be used for other purposes such as electrical signs, transparencies, kindergarten books, etc.

20 A further application of the invention is to advertising purposes in the formation of show cards, signs, price cards and the like; the tabs in this last containing suitable letters or figures in any desirable style, and 25 which when assembled in proper position on the base card or member, will form suitable reading matter.

Broadly speaking, the invention may be said to comprise a tab and a base member 30 having interlocking, flexible tongues and a multiplicity of slits to receive the tongues and permitting adjustment of the tab to a plurality of positions, the details of the invention being more fully set forth and described in detail in the accompanying specifications and drawings.

In the drawings: Figure 1 is a perspective view of a filing case having my improved tabs thereon. Fig. 2 is a perspective view of 40 one of the tabs. Fig. 3 is a plan view of one of the tabs specially adapted for advertising purposes. Fig. 4 is a plan view of a card or base member with advertising tabs thereon. Fig. 5 is a perspective view showing the tabs applied to index a book or the like. Fig. 6 is a plan view of an alternative form of tab, and also of the tab attached in position. Figs. 7, 8, 9, 10 and 11 are alternative views 45 of the tab, and also of the tab attached in position.

In the drawings, like characters of reference indicate corresponding parts in each figure.

As will be evidenced by the various embodiments of the invention shown in the drawings, the tabs may appear in a variety of forms. The invention is characterized by tongues formed either on the tab or on the member to which it is secured, adapted to interlock with certain of a plurality of suitable slits; thus in the preferred embodiment of the invention, the base member or sheet will be provided with a series of slits, and the tab with a plurality of tongues to take into certain of the slits. In order to give resiliency to the edges of the slits, transverse slits are preferably formed therein, thus converting the sides of the slits into flexible tongues. The portion of the members around the slit may if desired be reinforced to compensate for the weakening caused by punching the slit.

It is evident that the tab may be formed of any suitable material and may contain printing letters or numerals of any desired form.

The tab is preferably designed so as to be formed at low cost by suitable punching machinery, and the slits may also be formed by suitable hand-punching or slotting machines, and in cases where it is to be applied to a book or counting system, the slits may be conveniently arranged to be formed by hand punches or slotting devices.

One of the cheapest and most suitable materials for the formation of the tab, is the ordinary Manila paper or press board, as this gives the tongues the desired degree of flexibility.

Referring first to Figs. 1 and 2 of the invention, A represents the tab which has tongues 10 and 11 on opposite sides thereof and integral therewith. B represents a filing case to which the tab may be applied and this is formed along its upper edge with a series of slits 12 arranged in a transverse row and of such size as to receive the tongues, the distance between the slots being an aliquot part of the distance between the sides of the tab, whereby, the tabs may be supported at any desired position. Flexibility is given to the sides of the slits by forming transverse slits 13 and 14 across the upper and lower extremities of the slits proper, the three slits thus forming a shape corresponding to the letter I, and forming

on each side of the slit, tongues which will give a little, to receive the tabs when the tongues are inserted, as shown in the drawings.

- 5 Figs. 3 and 4 represent a modification of the invention in which a base member or card C is provided, having I-shaped slits arranged longitudinally and transversely in rows 15 and 16 respectively; tabs 17 being 10 provided having tongues 18 and 19 adapted to fit into certain of the slits. This form of the invention may be used for show cards, electric signs, transparencies and the like, the tabs being in the form of alphabets, sets 15 of numerals and the like, and being printed if desired in a variety of colors on opaque, transparent or translucent material thereby enabling novel effects to be produced.

In applying the invention to index a loose 20 leaf system, loose leaf ledger or bound book, the edges of the leaves of the book are formed with a row 20 of slits, similar to those shown in Fig. 1. These slits may be formed in any suitable way, and if desired, 25 a hand punch may be used for this purpose.

In the form of tab shown in Fig. 6, tongues 21 and 22 are provided on opposite sides, and a tongue 23 at the bottom, the member to which the tab is to be applied 30 having sets of three slits, 24, 25 and 26 to receive the tabs, slits 24 and 26 being substantially at right angle to slit 25. The slits are provided with small end slits corresponding to the slits 13 and 14 shown in 35 Fig. 1, thus making the slits I shaped.

The form shown in Fig. 7, is similar to that shown in Fig. 6, only the side tongues 27 and 28 are cut within the area of the original tab and extend in an opposite direction from the tongue 29, the slits being 40 parallel. This effects economy in cutting the tab, and may be more suitable for some purposes.

In the form shown in Fig. 8, a projecting 45 tongue 30 is formed on the tab and another tongue 31 is cut in the body portion, two parallel slits 32 and 33 being formed in the member to which the tab is to be secured.

In the form shown in Fig. 9, both tongues 50 34 and 35 are formed in the body of the tab, corresponding slits 36 and 37 being formed in the member to which the tab is to be secured.

In the form shown in Fig. 10, the parallel 55 slits 38 and 39 are formed in the tab itself, while the member or sheet to which the tab is to be secured, has tongues 40 and 41 to extend into the slits.

In the form shown in Fig. 11, the tab is 60 formed with projections 42 and 43 at opposite sides of the bottom, and the member to which it is adapted to be secured is formed with two tongues 44 and 45 adapted to fit closely to opposite sides of the upper por-

tion of the tab, and a bottom tongue 46 65 adapted to engage the base of the tab, the projections 42 and 43 extending between the tongues, and holding the tab in position, as illustrated.

It may be mentioned, that if desired, the 70 tabs themselves, or the surface in which the slits are formed, may be reinforced with cloth or suitable reinforcing material.

As many changes could be made in the above construction, and many apparently 75 widely different embodiments of my invention, within the scope of the claims, constructed without departing from the spirit or scope thereof, it is intended that all matter contained in the accompanying specification and drawings shall be interpreted as 80 illustrative and not in a limiting sense.

What I claim as my invention is:

1. In combination an indexing sheet having in a series of spaced slits along the edge cut 85 in such a manner as not to reduce the surface of the sheet, the portions between such slits normally lying in the same plane as the remainder of the sheet, and an indexing tab adapted to project beyond the edge of the 90 sheet and having tongues adapted to have resilient engagement with the slits, which tongues are adapted to lie flatly against the sheet.

2. An indexing or tabulating sheet of 95 flexible resilient material having a series of slits along the edge adapted to receive indexing tabs and means for giving extra resiliency to the side edges of the slit.

3. In combination an indexing sheet having 100 a series of spaced slits along the edge cut in such a manner as not to reduce the surface of the sheet, the portions between the slits normally lying in the same plane as the remainder of the sheet and an indexing tab 105 adapted to project beyond the edge of the sheet and having tongues extending in opposite directions, said tongues being adapted to have resilient engagement with the slits and to lie flatly against the sheet.

4. An indexing or tabulating sheet having 110 a series of spaced slits along the edge whose side edges are rendered resilient by cross slits located one at each end of and extending across the spaced slits.

5. An indexing or tabulating sheet having 115 a series of resilient tongues cut therein forming slits to receive tabs.

6. An indexing or tabulating sheet having 120 a slit of substantially I-shape adapted to receive part of an indexing tab and means to engage and hold another part of the indexing tab.

7. An indexing or tabulating sheet of 125 resilient material provided with a pair of substantially I-shaped slits so positioned with relation to each other that they may receive an indexing tab between them.

8. In combination a tab having tongues on opposite sides and a bottom tongue and an indexing sheet having a series of sets of slits along the edge, each set including side slits adapted to engage the side tongues and a bottom slit adapted to engage the bottom tongue, said tab being adapted to project beyond the edge of the sheet and being visi-

ble for indexing purposes when the sheet is in a vertical file or closed book.

10

In witness whereof I have hereunto set my hand in the presence of two witnesses.

PETER MACGREGOR.
